CORPORATION OF NEW YORK

GAME PACKAGE

Continuation of application Serial No. 195,445, filed May 31, 1927. This application filed August 14, 1929.
Serial No. 385,773.

This invention relates to improvements in the method or means of packing an article of merchandise and particularly to a package containing a "clock golf" game, and the 5 present application is a continuation by revival of our previous application, Ser. No. 195,445, filed May 31st, 1927.

The primary object of the invention resides in a means for compactly and attractively packing the parts which constitute a clock golf game into a container whereby the same may be elaborately displayed upon the removal of the cover of the container.

Another object of the invention is to provide a means for packing the parts of a clock golf game into a container so that the same may be shipped and carried without rattling and without disturbing the relative position of the parts.

20 A further object of the invention is the provision of a container having a removable horizontal partition therein provided with an opening centrally thereof for accommodating the cup of a clock golf game and about 25 which cup the numerical marking numbers which constitute part of the game are consecutively and radially arranged, the same having spikes for embedment in the ground, and which spikes pass through openings in the 30 partition for holding the marking members against radial shifting movement.

A still further object of the invention is to provide a clock golf package in which the parts which constitute the game are packed 35 within a circular container with the cup arranged centrally thereof, and the cup flag supported thereby and nested therein.

With these and other objects in view, the invention resides in certain novel construction and combination and arrangement of parts, the essential features of which are hereinafter fully described, are particularly pointed out in the appended claims, and are illustrated in the accompanying drawings, in 45 which:—

Figure 1 is a perspective view of the package with the cover removed.

Figure 2 is a vertical sectional view with the cover in position thereon.

50 Figure 3 is a collective perspective view

of the container, partition support and partition.

Referring more particularly to the drawing, the reference numeral 10 designates our improved package containing a clock golf game and which includes a round and relatively shallow container 11 which may be constructed of metal or other suitable material. Supported upon the bottom of the container 11 is a partition support 12 which is square in configuration and constructed of relatively stiff cardboard. The support 12 is of a size to easily fit within the round container and is of a height slightly less than the depth of the container for supporting a horizontal partition 13 below the top side walls thereof. The partition 13 is circular in configuration to snugly fit within the walls of the container and is constructed of stiff cardboard or the like.

70 The partition 13 is supported in spaced relation to the bottom of the container and is provided with a central opening 15 for accommodating the cup 16 of the game. The cup is of such a height as to extend slightly 75 above the top of the partition when the same is resting upon the bottom of the container.

Also constituting part of the game are numerical marking members 17, which members have their side edges cut on an angle with a common radii and which have their top and bottom edges curved on an arc common to the radii. This arrangement permits the marking members to completely fill the space 80 on the platform between the cup and the side walls of the container when in consecutive arrangement. The marking members 17 are provided with spikes 18 which extend from the undersides thereof for holding the numerals in a set position when driven into the ground. The numerical marking members range from one to twelve and as before mentioned the same are arranged consecutively 85 about the cup 16 in radial arrangement to simulate the dial of a clock, this being suggestive of the game itself. The spikes 18 of the numerical marking members extend through suitable spaced openings 19 provided in the horizontal partition 13 and serve to 90 95 100

prevent radial shifting of the members during shipment or carrying of the package.

A flag 20 which is part of the game is in the form of a metal disk and is of a diameter slightly less than the diameter of the cup 16 and is packed to lie over the top of the cup on a plane flush with the top sides thereof. The flag 20 is slidably mounted on a staff 21 so that the same may be moved to a position intermediate the ends of the staff for packing purposes, but which permits movement of the flag to one end of the staff for use. The other end of the staff is supported by passing the same through an opening 22 provided in a bridge piece 23 suspended from the side walls of the cup 16, and which staff is driven into the earth at the bottom of the cup for supporting the same in a vertical position. The staff when packed is seated in opposed notches or seats 24 provided in the top peripheral edge of the cup 16 so that the same lies flush with the top thereof. This also prevents shifting of the flag and staff during shipment. It may be mentioned that the staff is of a length to freely fit within the confines of the container.

A marking device 25 is usually furnished with a game of this kind for marking off the radial course with respect to the cup by which the required distance may be obtained for the placing of the numerical marking members 17 which constitute the tees. This marking device together with score cards may be packed within the cup and supported by the bridge piece 23 and concealed by the flap. A cover 26 fits over the open top of the container 11 for closing the same.

The numerical marking members 17 may be of any suitable color to stand out in contrast to the green grass on which a clock golf game is laid out, such colors as for instance red and white, the even numbers being colored red and the odd numbers being colored white.

From the foregoing description, it will be seen that we have shown a simple and attractive means for packing and displaying a clock golf game which will prevent damage to the parts during shipment and will induce the sale of the game when the cover is removed and the package placed on display.

While we have described what we deem to be the most desirable embodiment of our invention, it is obvious that many of the details may be varied without in any way departing from the spirit of our invention, and we therefore do not limit ourselves to the exact details of construction herein set forth nor to anything less than the whole of our invention limited only by the appended claims.

What is claimed as new is:—

1. An article of merchandise comprising a container, a horizontal partition supported within said container and having a central

opening therein, a cup resting on the bottom of said container and extending through said opening, and numerical members supported upon said partition and arranged radially about said cup.

2. An article of merchandise comprising a circular container, a horizontal partition supported within said container and having a central opening therein, a cup resting on the bottom of said container and extending through said opening, and numerical members supported upon said partition and arranged radially about said cup in consecutive order.

3. An article of manufacture comprising a container, a hollow core disposed in said container centrally thereof, and marking members within said container and disposed in radial arrangement in the space between said hollow core and the side walls of said container.

4. In combination with the cup and numerical marking members of a clock golf game, a container, a horizontal partition supported within said container and having a central opening therein for the reception of said cup, said numerical marking members being supported upon said partition in radial arrangement about said cup.

5. In combination with the cup and numerical marking members of a clock golf game, a container, a horizontal partition supported within said container and having a central opening therein for the reception of said cup, said numerical marking members being supported upon said partition in radial arrangement about said cup, a disk constituting a marking flag for said cup and mounted on a staff, the periphery of said cup being provided with opposed notches for receiving said staff to permit said disk to overlie the top of said cup and be disposed flush with the sides thereof.

6. An article of merchandise comprising a container, a horizontal partition supported within said container in spaced relation to the bottom thereof, said partition having suitably spaced openings therein, numerical members, and legs extending from said numerical members and passing through the respective openings in said partition.

7. An article of merchandise comprising a container, a partition having suitably arranged spaced openings therein, means for supporting said partition within said container in spaced relation to the bottom thereof, marking members of segmental configuration, and legs extending from the underside of said marking members and passing through the respective openings.

In testimony whereof we hereby affix our signatures.

NORMAN E. WOLF.

WALTER F. WOLF.
